UNITED STATES PATENT OFFICE.

CHARLES H. ANDERSON, OF CINCINNATI, OHIO.

STEEL PASSENGER-CAR.

1,148,000.

Specification of Letters Patent. Patented July 27, 1915.

Application filed December 17, 1914. Serial No. 877,699.

To all whom it may concern:

Be it known that I, CHARLES H. ANDERSON, a citizen of the United States, and a resident of Cincinnati, in the county of 5 Hamilton and State of Ohio, have invented certain new and useful Improvements in Steel Passenger-Cars; and I do hereby declare the following to be a full, clear, and exact description of the invention, such as 10 will enable others skilled in the art to which it appertains to make and use the same.

My invention relates to an improvement in steel passenger cars, and especially to an improvement in the construction of eaves 15 plate or letter boards for the same.

The object of the invention is to provide an eaves plate or letter board constructed to be applied directly to the side posts without the employment of intermediate brackets, 20 and form a continuous pocket or housing for the cork or other heat and sound non conducting lining which is applied to the inner surfaces of said plate.

With this object in view my invention 25 consists in the details of construction as will be more fully explained and pointed out in the claims.

In the accompanying drawings, Figure 1 is a view in side elevation partly in section 30 of the upper portion of one side of a car, and Fig. 2 is an enlarged view of the eaves plate and parts to which it is connected.

1 represents a steel T-bar which constitutes a vertical post for sustaining the sides 35 and roof of the car body and also serves as the side frames of the windows in which the sashes 2 and 3 are mounted. Upon the upper and curved portions of the T-bars 1 is secured the steel roof plate 4, riveted or 40 otherwise secured at its side edges to the upper edge of the eaves plate or letter board 5. The lower edge of the eaves plate, which extends throughout the length of the car is bent upon itself to form the depending 45 flange 6, and is then bent inwardly as at 7 and upwardly as at 8, the upwardly bent portion 8 being parallel with the plate 5, but removed therefrom a distance sufficient to hold the plate 5 in a plane beyond the window sash 3, and forms a pocket or housing 50 in which cork or other insulating material 9 may be conveniently packed and supported, this pocket or housing extending the whole length of the car and continuous from end to end.

The upper portion of the eaves plate is bent inwardly at a point adjacent the side edge of the roof, and projects upwardly a distance sufficient for its secure attachment to the roof supports to which it is riveted, 60 the steel roof plate 4 overlapping the upper edge of the eaves plate and firmly riveted to the same. A layer of cork or other material 10 which will serve as insulator of electricity and also of heat, is placed upon the roof plate 65 and is retained in place by the cover 11 of canvas or other suitable material. The lower edge of the canvas cover 11, is secured to the wooden batten 12, seated against the shoulder 13 of the eaves plate, 70 which shoulder is formed by bending the upper edge of the plate inwardly toward the side posts; the batten being held in place by a steel band 14 secured by bolts passing through to the batten and side posts, or by 75 rivets to the eaves plate. The lower end of the eaves plate forms a housing for the upper end of top sash 3, the flange 6 of said plate overhanging said sash sufficiently to prevent the outward displacement of the 80 same and also prevent the entrance of water above the sash. The upwardly bent portion 8 of the lower edge of the eaves plate, rests against and is riveted directly to the side posts, and it together with the inwardly bent 85 portions 7 and 13 sustain the plate in the proper position without the employment of brackets which have heretofore been universally used for securing the eaves plate to the side posts, and permits the insulating 90 filling or lining to be continuous from end to end of the car instead of from bracket to bracket as heretofore.

It is evident that many slight changes 95 might be resorted to in the relative arrangement of parts shown and described without departing from the spirit and scope of my invention. Hence I would have it understood that I do not wish to confine myself to the exact construction and arrangement of 100 parts shown and described, but

Having fully described my invention what I claim as new and desire to secure by Letters-Patent, is:—

1. In steel car construction, the combination of side posts and an eaves plate having an upwardly, inwardly and upwardly bent lower edge, the two upward bends forming respectively a pocket below the eaves plate 105 for the top edge of the upper sash and a 110

pocket at the rear of the plate, the upward bent portion at the inner free edge of the plate being secured to the side posts.

2. In steel car construction, an eaves plate 5 having an inwardly and upwardly bent upper edge, and an upwardly, inwardly and upwardly bent lower edge, the upward bends at the lower edge of the plate forming respectively a pocket below the eaves plate for 10 the top edge of the upper sash, and a pocket at the rear of said plate for supporting an insulating lining.

3. In steel car construction, an eaves plate bent inwardly and upwardly at its upper 15 edge the inward bend forming a shoulder or abutment for the roof covering, and bent inwardly and upwardly at its lower edge the upward bent portion of both edges being adapted for direct attachment to the roof

supporting member of the car and the upward bend at the lower end forming a continuous pocket at the inner side of the plate.

4. In steel car construction, the combination of side posts, an eaves plate having inwardly and upwardly bent upper and lower 25 edges the said upwardly bent portions being for direct attachment to the side posts and the upwardly bent portion at the lower edge forming a pocket for supporting an insulating lining.

In testimony whereof, I have signed this specification in the presence of two subscribing witnesses.

CHARLES H. ANDERSON.
